WILLIAM WELBOURNE, OF PRESTON, GREAT BRITAIN.

Letters Patent No. 65,849, dated June 18, 1867.

IMPROVED TEA-CANISTER.

The Schedule referred to in these Letters Patent and making part of the same.

TO ALL WHOM IT MAY CONCERN:

Be it known that I, WILLIAM WELBOURNE, of Preston, in the county of Lancaster, Kingdom of Great Britain and Ireland, have invented certain improvements in Canisters for containing Tea, etc.; and I do hereby declare the following to be a full, clear, and exact description of the same, reference being had to the accompanying drawing, and to the letters of reference marked thereon.

The invention is designed for the purpose of preventing the accumulating of tea dust or similar deposits at the bottom of canisters containing tea or other substances, and also for enabling the attendant to take tea from the canister without touching it with the hand or removing the canister from the shelf; and the improvements consist in subdividing a canister box or receptacle into several vertical compartments, transversely from side to side, the said divisions extending from the top of the canister to a slanting platform placed inside the canister a slight distance above the bottom thereof; this distance or space being left conveniently large to allow a small scoop to be inserted therein, a swinging or sliding door being placed in the lower portion of the canister to admit the scoop. The middle compartment in the canister is provided with a door which, when closed, divides the said compartment in two, the back one having a clear open passage through the diagonal platform into the space in the bottom of the canister, and the bottom or diagonal platform of the two outer or side compartments are provided with a sliding door, which, when withdrawn or opened, also allow an open thoroughfare from the said side compartment into the aforesaid space in the bottom of the canister. Thus, when the canister is filled, with tea, for example, the density thereof in the middle compartment has been discharged, at which time the weight of tea in the front compartment forces open the said door so as to effect a communication for discharge through the same passage into the bottom space; so soon and as the centre compartment is empty the slide in one of the side compartments is withdrawn, thereby allowing the tea contained therein to be discharged, and so on in like manner with the opposite compartment. The discharge of the tea from the several compartments in the lower space of the canister, as described, is regulated according to the quantity withdrawn from such space by the scoop.

In order to enable others to make and use my invention, I will now proceed to describe its construction and operation, reference being had to the accompanying drawing, in which—

Figure 1 represents a front view, shown in elevation, of a canister or receptacle, its internal arrangement being shown in dotted lines.

Figure 2 represents a side vertical section of the canister.

Figure 3 represents a plan view of the same.

Figure 4 represents a vertical side section of a square canister, supplied with the improved internal arrangement, and

Figure 5 represents a plan view of the same.

Figure 5 represents a plan view of the same. In figs. 1, 2, 3, 4, and 5, α is the canister or receptacle, which is internally subdivided into the compartments b b' , the divisions extending from the top of the canister to the slanting platform c , which is securely placed inside at a small distance above the bottom d . The division or space e formed between the platform c , and the canister bottom d is conveniently large to admit a small scoop which is to be inserted therein through the doorway f . The middle compartment b' of the canister is provided with the swing-door g , which, when closed, divides the said compartment in two, the back one, b' , having a clear opening or passage, h , through the platform c into the space e . The bottom or diagonal platform c of the two outer or side compartments b b' are provided with sliding-trap or drop-doors i i , which, when withdrawn or opened, also allow an open passage from such compartments into the space e . Thus, when the canister α is filled with tea, the swing-door g , being closed, allows the back compartment b' to become discharged as the tea is withdrawn by the scoop from the space e , and as soon as the compartment is empty the weight of tea in the front compartment forces open the door g , effecting thereby a communication for discharging through the same passage into the bottom space e . The side compartments b b' are being severally emptied in like manner when the slides i i are withdrawn, so as to open the passages between the said compartments b b' and the space or chamber e . The square canister, seen in fig. 4, is internally divided into two compartments b b' . These compartments being again divided by the divisional doors g g , terminate on the diagonal platform c . The back portion of the platform is secured by a hinge to the

canister, and is so constructed that when supported by the leg *k*, the tea is prevented falling into the space *e*, but when let down a passage is opened between the compartment of the canister and the space *e*, the discharge of the contents of each being effected directly through these two apertures, opened and closed by the hinged platform, or, if the platform be inclined from the sides to the centre, both compartments may be discharged through one central aperture into which the scoop is inserted.

I claim as my invention, and desire to secure by Letters Patent—

A canister, having partitions and doors, arranged and operating substantially in the manner and for the purpose described.

In testimony whereof I have signed my name to this specification in the presence of two subscribing witnesses.

WILLIAM WELBOURNE.
